UNITED STATES PATENT OFFICE.

WALTER A. HOLBROOK, OF MILWAUKEE, WISCONSIN.

RAILWAY FREIGHT-CAR.

No. 799,905.

Specification of Letters Patent.

Patented Sept. 19, 1905.

Application filed January 19, 1905. Serial No. 241,745.

To all whom it may concern:

Be it known that I, WALTER A. HOLBROOK, a citizen of the United States, and a resident of Milwaukee, in the county of Milwaukee and State of Wisconsin, have invented certain new and useful Improvements in Railway Freight-Cars; and I do hereby declare that the following is a full, clear, and exact description thereof.

10 My invention consists in certain peculiarities of construction and combination of parts hereinafter particularly set forth, with reference to the accompanying drawings, and subsequently claimed, its object being to economize the production of strong and durable railway freight-cars.

Figure 1 of the drawings represents a side elevation of a freight-car body in accordance with my invention, partly broken away and 20 in section; Fig. 2, a transverse sectional view of the same on the plane indicated by line 2 2 in Fig. 1, and Fig. 3 a transverse sectional view of a fragment of the car provided with a flat bottom and dumping-door.

25 Referring by letter to the drawings, A indicates each of a pair of lower central steel channel-beams on suitably-bent lower members B of metallic body-bolsters, the upper horizontal members C of which are supported 30 on said beams. Angular metallic clips D embrace the ends of beams A and are made fast at their ends to horizontal stay-bars E, supported on said beams parallel to the upper members of the body-bolsters. Other steel 35 channel-beams F are fastened on the bolsters and bars aforesaid, and end braces F' are connected at their ends to the latter beams. The aforesaid body-bolsters and end clips serve in practice as supports for the draw- 40 bars of the car. Depending side trusses G and stays H are made fast to the beams F, and in rigid hook connection with these beams are the ends of metallic rests I at suitable intervals apart, the construction and ar- 45 rangement of parts thus far described constituting the underframing of the freight-car herein specified.

The body J of the car is tubular, and in practice it consists of a plurality of suitably-bent plates of iron or steel riveted together similar to the construction of the body of an ordinary tank-car. The car-body is supported on bolsters and rests I of the underframing, to which it is fastened by suitable means. 55 Embracing the car-body are metallic bands K, fastened at their ends to the beams F of

the underframing, and other means may be employed to insure permanent union of said car-body and underframing. The sides of the car-body are provided with openings into angular lateral extensions J' of said body, and supported on these car-body extensions are track-rails L for the hangers M of metallic sliding doors N, the lower ends of which are shown bent to embrace under flanges P of said extensions.

The top of the car-body is shown provided with openings closed by doors Q, and a runway R as well as a hand-rail S are shown supported over said car-body. Ladder-rails T are shown attached to a side of the car-body, and in Fig. 1 a normally plugged clean-out opening U is shown in the bottom of said car-body.

As shown in Fig. 3, the bottom of the car-body may be flat and provided with a dumping-door V, that is held closed by a suitably-arranged turn-button W or other suitable means. Steel braces, similar to the one X shown in Fig. 3, may be made fast at their 75 ends to the beams F to strengthen the underframing and supplement the rests I, as the direct supports for the flat-bottom tubular car-body and various modifications of detail may be made in the general construction of 80 85 said underframing and car-body without departing from my invention.

From the foregoing it will be understood that I provide a tubular all-metal freight-car for the hauling of general merchandise, and 90 the same will be found very strong and durable in practice.

Having thus described my invention, what I claim as new, and desire to secure by Letters Patent, is

1. A railway freight-car having a tubular body provided with side openings and lateral extensions surrounding the openings, track-rails supported on said extensions of the car-body, and sliding doors hung on the rails.

2. A railway freight-car having a tubular body provided with side openings and lateral extensions surrounding the openings, track-rails supported on said extensions of the car-body, and sliding doors hung on the rails and 100 engaged at their lower ends with flanges of the aforesaid body extensions.

3. A railway freight-car having an underframing comprising a pair of central lower channel-beams, body-bolsters having the members thereof under and over the said beams to which they are connected, clips embracing

the ends of the aforesaid beams, bars on the beams in connection with said clips, other beams on the bolsters and bars and rests supported in connection with the latter beams; a tubular body on the rests, and means for securing the body in place.

4. A railway freight-car having an underframing comprising a pair of lower central channel-beams, body-bolsters having the members thereof over and under said beams to which they are connected, other beams on the

bolsters, and braces between the latter beams; a flat-bottom tubular car-body on the braces, and means for securing the body in place.

In testimony that I claim the foregoing I 15 have hereunto set my hand, at Milwaukee, in the county of Milwaukee and State of Wisconsin, in the presence of two witnesses.

WALTER A. HOLBROOK.
